United States Patent Office

Des. 195,475
Patented June 18, 1963

195,475

PIE TRAY OR THE LIKE

James B. Swett, Barrington, R.I., assignor to Rexall Drug and Chemical Company, Los Angeles, Calif., a corporation of Delaware

Filed Mar. 7, 1962, Ser. No. 69,123

Term of patent 14 years

(Cl. D44—10)

FIG. 1

FIGURE 1 is a perspective of a pie tray showing my new design; and,

I claim:

The ornamental design for a pie tray or the like, as shown.
